UNITED STATES PATENT OFFICE.

EDMUND HEROLD OF BROOKLYN, NEW YORK.

INDEX-CLIP.

1,055,397.

Specification of Letters Patent. Patented Mar. 11, 1913.

Application filed January 29, 1909. Serial No. 474,969.

To all whom it may concern:

Be it known that I, EDMUND HEROLD, a citizen of the United States, residing at Brooklyn, in the county of Kings and State 5 of New York, have invented new and useful Improvements in Index-Clips, of which the following is a specification.

This invention relates to index clips, and has for an object to provide a device of this 10 character which will be particularly desirable and adapted for use by bookkeepers or the like and to provide simple and effective means for attaching the article to the leaves of a book.

15 A further object is to provide a clip with detachable index card carrying means.

Other objects and advantages will be apparent as the nature of the invention is better set forth, and it will be understood that 20 changes within the scope of the claim may be resorted to without departing from the spirit of the invention.

In the drawing, forming a portion of this specification and in which like numerals of 25 reference indicate similar parts in the several views:—Figure 1 is a plan view of the index clip. Fig. 2 is a similar view showing a slightly modified form of my invention. Fig. 3 is a detail section taken on the line 30 5—5 of Fig. 1. Fig. 4 is a view similar to Fig. 1 showing another modified form of my invention.

Referring now more particularly to the drawing, and with particular reference to 35 Figs. 1 and 3, there is shown an index clip comprising a clip 1 formed from a single piece of resilient wire bent to form an arm 2 having one end bent downwardly as shown at 3, outwardly as shown at 4 in parallel relation to the arm 2 and upwardly in 40 concavo-convex form as shown at 5. The portion 5 carries an arm 6 disposed in spaced parallel relation to the arm 2 and is bent downwardly as shown at 7, inwardly as shown at 8 and is finally bent at right 45 angles as indicated at 9 which last named portion is yieldingly engaged with a portion of the arm 2.

An index card retaining member is shown 50 at 10 and is preferably stamped to form parallel spaced flanges 11 between which the edges of an index card 12 are confined. The retaining element in this form of my invention, is of rectangular form and one of 55 the flanges 11 is slit as shown at 13 to provide a lip 14. The arm 2 of the clip is

bent at one end to form an arm 15, and this arm is bent at one end at right angles as shown at 16, and the portion 16 is bent at one end as shown at 17 to lie in parallel relation with respect to the arm 15. The construction of the clip is such that a portion of the arm 2, and the portions 15, 16 and 17 may be confined between the flanges 11 of the retaining element as clearly shown 60 in the drawing. The index card 12 is colored differently on both sides, and it may be mentioned that I preferably use the colors "Red and White", the white indicating that entries are to be made on a particular 65 leaf of a book, and the red indicating that the page has been completed and all entries made.

The arm 2 and the portions 3 and 4 form one element of the coöperating parts of the 75 clip while the parts 5, 6, 7, 8 and 9 form the other element of the said coöperating parts and as illustrated, the portions 4 and 6 by being connected by the concavo-convex portion 5 forms a free manipulating portion 80 A which is located directly at one side of the card holder so that when it is desired to engage the clip with the leaf of a book or with any other object the said part A can be conveniently manipulated so as to properly associate the said companion elements 85 of the clip with such leaf.

The part A is located immediately at the extremity of the arcuate portion 5, as shown in Fig. 1, and its location with respect to the portion B at the opposite extremity of the arcuate portion provides therewith a stop. The portions A and B are located immediately at one side of the card retainer and they are spaced therefrom so that when 90 embracing the leaf or object to which they are to be fastened they will hold the card retainer in spaced relation and prevent it from shifting or becoming accidentally displaced or working between the leaves of a 95 page or the like.

In the form of my invention shown in Fig. 2, the card 17 is of an elliptical form, and the retaining element 18 is of a corresponding form to receive the card. The 100 clip 19 in this form of my invention is approximately the same as that previously described, the difference being in the provision of a straight arm 20 which I use in lieu of the concavo-convex portion 5 of the preferred form of my invention, and as clearly 110 shown, the said arm 20 is offset as indicated

at 21 to increase the strength and efficiency of the article.

While I have mentioned in the foregoing that the index cards are differently colored, it is obvious that I may employ characters or other distinguishing means for accomplishing the desired end. The index cards herein referred to are coated upon both sides with silicate slate so that marks upon said cards can be readily erased, when desired, and as protection for the cards, I provide them with transparent celluloid or like material to prevent soiling of the cards as will be readily understood.

Upon reference to Fig. 1 of the drawing, it will be seen that the clip is so constructed as to allow the index card to be turned in between the leaves of a book so that it will be out of the way, the clip, at the same time acting as a book mark and effectively serving to hold the place.

Upon reference to Fig. 4 of the drawing, it will be seen that the retaining member 38 is somewhat similar to the retaining member 10 shown in Fig. 1 of the drawing, but in this form the flanges 39 at the sides of the member are cutaway at their upper ends so that the index card in the transparent material can be easily engaged with the member 38 or removed therefrom when it is desired to erase from the index card characters or other indicating marks.

I claim:—

In an index clip, the combination with a card retainer of rectangular formation, of a support for said retainer formed from a single length of wire having one of its terminals bent to conform to the configuration of said retainer and positioned therewithin, the intermediate portion of said support projecting laterally from within the said retainer and at the lower end thereof for some distance and then bent downwardly, then laterally parallel to said intermediate portion, then upwardly and crossing said intermediate portion; then outwardly beyond and parallel to said intermediate portion; then downwardly and below said intermediate portion, then inwardly parallel with said intermediate portion and crossing said first mentioned downwardly bent portion; and terminating in an upwardly bent arm crossing said intermediate portion adjacent its outer end, whereby a three point gripping action is provided for, thereby increasing the effectiveness of the device.

In testimony whereof I affix my signature in presence of two witnesses.

EDMUND HEROLD.
